UNITED STATES PATENT OFFICE.

EDWARD B. PARSONS AND JAMES W. BULLINGTON, OF OILTON, OKLAHOMA, ASSIGNEES
TO OKLAHOMA MAGNETIC POST CO., OF OILTON, OKLAHOMA.

ELECTRICAL CONNECTOR.

Application filed February 23, 1921. Serial No. 447,105.

To all whom it may concern:

Be it known that we, EDWARD B. PARSONS and JAMES W. BULLINGTON, citizens of the United States, residing at Oilton, in the county of Creek and State of Oklahoma, have invented certain new and useful Improvements in Electrical Connectors, of which the following is a specification.

The invention relates to electrical connectors for magnetos and more particularly to a type of the same adapted for use in conjunction with the magnetos of Ford automobiles, etc.

In the operation of magnetos on automobiles in general, dimming of the lights, and mis-firing of the spark plugs, is primarily due to presence of the accumulation of dirt on the terminals, or terminal in the magneto, and provision is made for the removal of the terminal for cleaning, and this is particularly true of the construction and arrangement now employed on Ford automobiles.

The main object of the present invention is therefore to provide for an extremely simple, inexpensive and efficient terminal construction, whereby the removal of the same is facilitated for the quick cleaning of the contact point thereof, and its replacement back into operative position.

With the foregoing and other objects in view, the invention resides in the certain new and useful construction and arrangement of parts as will be hereinafter more fully described, set forth in the appended claims, and illustrated in the accompanying drawing, in which:—

Fig. 1 is a fragmentary longitudinal section of the magneto housing showing the terminal embodied therewith,

Fig. 2 is a fragmentary section of the top wall of the housing showing the terminal and its mounting in plan,

Fig. 3 is a vertical section taken on the line 3—3 of Fig. 2, and,

Fig. 4 is a detail, in perspective, showing the locking column for retaining the terminal in position.

Referring to the drawing, the numeral 10 indicates the magneto within the housing 11, and 12 the commutator of the magneto 10 in position below the terminal opening of the housing, all of usual construction and arrangement as now obtaining in the Ford type of automobiles.

The removable terminal for the magneto 10 is supported in the casing of substantially cylindrical form as in 13, having an annular flange 14 at its lower end and by means of which it is to be secured to the housing 60 through the medium of suitable fastenings or screws 15. The casing 13 is formed with a central lower bore 16 in registry with a circular opening 17 formed in the housing 11 immediately above the commutator 12 65 of the magneto 10, and an upper bore 18 of a greater diameter than the bore 16 concentric with respect to the latter. Seated on the shoulder 19 between the bores 16 and 18 is a member 20, of substantially frusto-conical 70 form and made of any suitable insulated material, the upper end of which is projected above the top edge of the casing 13. Formed with the member 20 is a cylindrical sleeve portion 21 which extends downwardly of 75 the bore 16 and projects through the opening 17 and into the housing 11. Interposed between the shoulder 19 and the shoulder portion of the member 20 overlying the same, is a gasket 22 of rubber or the like. 80 Extending through the member 20 is a terminal rod 23, of a conducting material of brass or the like, which has its upper projected end threaded to receive a washer 24 and a circuit lead (25) binding nut 26. The 85 lower end of the rod 23 is projected concentrically within the bore of the sleeve 21 and has secured to its free end a coiled spring 27, which, in turn, has its lower end projecting below the end of the sleeve 21 90 and supports on its free end a contact 28 tensioned against the commutator 12 of the magneto. For the purpose of retaining the member 20 firmly in position within the casing 13, a cylindrical member 29 is formed 95 with a tapered bore adapted to be fitted over the similarly tapered upper end of the member 20, and is arranged to engage the latter at a point so as to have its upper end disposed in the plane of the top edge of the 100 casing 13. The member 29 is provided with circular lugs 30 one diametrically opposite the other and projecting laterally therefrom, which lugs 30 are adapted to be engaged in complementary inclined angular slots 31 105 formed in the wall of the upper portion of the casing 13 one leg of each slot 31 opening through the top edge of the latter. When the lugs are inserted downward of the open legs of the slots 31, the free projecting ends 110

- of the same can be grasped by the fingers so as to move the collar around the conical surface of the member 20 and the pins to the closed ends of the slots.
- 5 In the use of the terminal, the member 20, with its sleeve portion 21, has assembled therein the rod 23 carrying the spring 27 and the contact 28, by inserting the same upward of the sleeve portion 21 and securing 10 the parts in position by means of the washer 24 and the binding nut 26. The member 20, with these members assembled with the same, is now inserted into the casing 13, after the gasket 22 has been seated on the 15 annular shoulder 19, and the member 29 is then placed over the upper end of the member 20 with the lugs 30 in registry with the open ends of the slots 31. The depth of the slots 31 is sufficient to act in a manner to 20 exert a downward pressure on the lugs 30, when the same are moved endwise of the slots, so as to effect a slight compression of the gasket 22 under the shoulder portion of the member 29, whereby an airtight joint is 25 established between the same. The terminals are now ready to receive the terminal lead 25 of the circuit of the automobile. Should any trouble be experienced as by the dimming of the lights, or misfiring of the 30 spark plugs be heard, it may indicate an accumulation of dirt on the contact 28, and the same is to be inspected and cleaned, by merely turning the lugs 30 in the slots 31 and withdrawing the member 29 and the 35 member 20, either separately or together, and with or without the disconnection of the lead 25 from the rod 23, as may be desired.
- It is to be understood, that, while we describe the invention particularly in connection with magnetos as used on Ford automobiles, the same is capable of a more general use wherever similar devices may be employed or on any other type of automobile, and, also, that various changes in the 40 details of construction and arrangement of parts may be resorted to without departing from the spirit and scope of the invention.
- Having thus fully described the invention, what is claimed, is:—
1. In a device of the class described, a 50 cylindrical casing having a lower bore and an upper bore of greater diameter than the lower bore, an insulated body of substantially frusto-conical form within the upper bore of said casing, and having a sleeve portion depending in the lower bore thereof, a terminal contact carried by the upper portion of said insulated body and depending through the sleeve portion thereof, a member encircling the upper portion of said insulated body within said housing, slots formed in the opposed wall of said casing, and lugs carried by said member adapted for engagement with said slots, whereby to removably secure said body in position. 55
2. In a device of the kind described, a cylindrical casing, an insulated body within said casing, a terminal contact carried within said body and depending below the lower end thereof, a member encircling a 60 portion of said insulated body within said casing, slots formed in the opposed wall of said casing, and lugs carried on said member and adapted for engagement with said slots, whereby to removably secure said body in 65 position.
3. In a device of the class described, a cylindrical casing having a lower bore and an upper bore of greater diameter than the lower bore, an insulated body having an 70 upper portion of substantially frusto-conical form seated in the upper bore of said body, and a sleeve portion depending into the lower bore of said casing, a contact terminal carried in the upper portion of said insulated body and depending through the sleeve portion thereof, a locking member fitted over the upper end of said insulated body, slots formed in the wall of said casing, and lugs formed with said locking member 75 adapted for engagement with said slots whereby to removably secure said insulated body in position. 80
